UNITED STATES PATENT OFFICE.

RICHARD BEAUMONT, OF KANKAKEE, ILLINOIS.

WATER-HEATER.

SPECIFICATION forming part of Letters Patent No. 687,419, dated November 26, 1901.

Application filed March 25, 1901. Serial No. 52,730. (No model.)

To all whom it may concern:

Be it known that I, RICHARD BEAUMONT, of Kankakee, in the county of Kankakee and State of Illinois, have invented certain new and useful Improvements in Water-Heaters; and I do hereby declare that the following is a full, clear, and exact description thereof, reference being had to the accompanying drawings, and to the letters of reference marked thereon, which form a part of this specification.

This invention relates to an improvement in water-heaters of that type comprising a series of water-drums supported within a shell over a combustion-chamber.

The device consists in the matters herein-after set forth, and more particularly pointed out in the appended claims.

In general terms a device which embodies the principal features of my invention comprises a combustion-chamber, an outer cylindrical shell rising therefrom, and a series of cylindrical water-drums supported in the shell over the combustion-chamber, the upper of said drums supporting a smoke-chamber and the remaining drums being suspended from the upper drum in tandem within the shell.

In the drawings, Figure 1 is a view in vertical section of a water-heater embodying the salient features of my invention. Fig. 2 is a view in cross-section through the heater on line 2-2 of Fig. 1. Fig. 3 is a view in cross-section through one of the drums, taken on line 3-3 of Fig. 1.

Referring to the drawings, A represents a combustion-chamber of ordinary pattern. As shown herein, it is provided with the usual grate a and ash-pit a' and side walls a^2 , which extend upwardly above the grate, so as to form a circular chamber with flaring sides. Extending upwardly from the upper margin of said combustion-chamber and supported thereon is a cylindric metallic inclosure or shell B. This may be inclosed, if preferred, in masonry setting C, as herein shown, or may be lagged out and jacketed. The upper end of said shell supports on its upper margin a water-drum D, formed of cast-iron, or built of sheet metal, if preferred. Said water-drum D is formed with flues and a deflector-plate, as hereinafter more fully described, and carries an upper smoke-chamber d' , made, pref-

erably, of sheet metal and adapted to lead the smoke and gases of combustion from the flues of the drum D to a suitable smoke-pipe E. Obviously said smoke-chamber may be of any desired form. As herein illustrated, it is formed by a cylindrical side wall d^3 and an upper end wall d^3 , the latter having an aperture adapted for connection with the smoke-pipe E in the usual manner. The drum D, which is of less diameter than the shell B and is dependent therein, is formed by a flat upper plate d^4 , which extends over the upper margins of the shell B and is secured thereon at its margin d^5 , so as to form a tight joint, a cylindrical side wall d^6 , depending from the plate d^4 within the shell B and of considerably less diameter than the internal diameter of the shell B, and by a horizontal bottom plate d^7 , secured to the lower margin of the side wall d^6 . Passing through said drum are a plurality of vertical flues F, said flues being arranged symmetrically in said shell or drum and being formed with converging side walls d^8 , so as to be in form truncated cones. The upper plate d^4 of said drum is provided with an upwardly-projecting boss or nipple d^9 , which is centrally located and is provided with an aperture suitably screw-threaded or otherwise fitted for connection with a water-outlet pipe G, which extends upwardly therefrom to the smoke-chamber d' and into the smoke-pipe E, from which it is led in any direction desired. A depending boss d^{10} is centrally located on the lower surface of the bottom plate d^7 of the drum and is likewise provided with an aperture screw-threaded for pipe connection, said aperture being in approximate alignment with the aperture of the upper nipple d^9 . Midway between the upper and lower end plates d^4 and d^7 of the drum D is a horizontal deflector-plate H, which is supported by resting on or being connected with the side walls d^8 of the flues F. By this arrangement of the parts the deflector-plate H is interposed in the line of flow between the upper and lower apertures of the bosses or nipples d^9 and d^{10} . Suspended from the drum D by means of a connecting-pipe I, secured by screw-threads in the aperture of the depending nipple d^{10} , is a water-drum K, which is similar in the main to the drum D, being provided with upper and lower horizontal walls

k' cylindrical side wall k², and preferably equal in external diameter to the side wall d⁶ of the drum D, and flues F', similar in shape to the flues F and equal in number. The upper horizontal end wall k projects beyond the side walls k² a sufficient distance to form an annular horizontal flange k³, whose external diameter is slightly less than the internal diameter of the shell B, so as to afford a narrow passage between the flange and the shell. The drum K is further provided with an interior deflector-plate H', similar to the deflector H, and outer bosses or nipples k⁴ k⁵, centrally apertured and internally screw-threaded for connection with the connecting-pipe I and a dependent connecting-pipe I'. Said pipe I' serves as a connection and support for a series of two or more drums K' K² dependent therefrom, the intermediate drums, as K', being similar in every respect to the drum K, and the lowest one, as K², of the series having no deflector-plate and having in place of the lower boss in the center of its bottom plate a side boss or nipple k⁶, centrally apertured and screw-threaded for the reception of a feed-water pipe L, which extends therefrom out through the wall of the shell D and the side of the furnace for convenient connection with any water-supply. In mounting the drums it will be observed that the connecting-pipes I, I', and I² are so fitted that when the drums are screwed home thereon the flues of each drum are staggered with respect to the flues of the adjacent drums.

The operation of the device is obvious. The products of combustion and the heat arising from the combustion-chamber A are conducted by the walls of the shell B to the lower drum K², against which they impinge and are divided, a part passing upwardly through the converging walls of the flues F³ and a part passing up between the side walls of the drum and the side walls of the shell B around the upper horizontal flange of the drum. The currents from the flues strike against the bottom wall of the drum above it owing to the staggered position of the flues and are diverted along the bottom of the drum to the flues, through which they pass up to and against the bottom of the succeeding drum K'. The part of the current passing around the side wall of the drum is partially arrested by the horizontal flange thereof, so as to thoroughly heat the side walls, and then escapes around the flange and passes up to the next drum, where it is again momentarily checked by the flange. Thus the heat-currents from the combustion-chamber are caused to pass over nearly the entire surface of each drum until they finally reach the smoke-chamber d' above the upper drum D, from whence they escape through the smoke-pipe E. In this manner the greater portion of the drum-surfaces are heated by direct contact with the hot gases. The funnel shape of the flues affords a comparatively large wall-

surface, which, owing to its position with regard to the currents of hot gases, is highly heated. Water is fed into the lowest drum K² through the pipe L. There it comes in contact with the heated bottom plate and the side of said drum and the flaring side walls of the flues F³ and thence passes upward through the connecting and supporting pipe I² into the next drum K'. Here it impinges against the deflector-plate H², which causes it to flow outwardly around the walls of the flues F² and the side walls of the drum, so as to come in contact with the heated surfaces thereof before it passes up through the connecting-pipe I' into the next drum, where it is again deflected by the plate H'. By this means a thorough circulation of the water against the thoroughly-heated walls of the drums is insured before the water passes through the entire series of drums and reaches the discharge-pipe G.

An important advantage in this form of construction is in the method of supporting the drums in the shell B. The drums hang entirely free from the shell B and are therefore independent therefrom and are not subjected to any strain of internal expansion. Furthermore, they are very easily mounted and dismounted for repairs or replacing the parts, it only being necessary to screw each drum home on its connecting central pipe. Any amount of heating-surface can be obtained by mere multiplication of the drums and proportionate increase in the size of the combustion chamber and shell B without the usual complication arising in many forms of construction of water-heaters due to increase of weight and the multiplication of supporting devices.

It will be understood that I do not limit myself to the specific form of construction herein shown, except as set forth in the appended claims.

I claim as my invention—

1. A water-heater comprising a combustion-chamber, an outer shell extending upwardly therefrom, and a series of water-drums within said shell, the uppermost of said drums having its end wall extended beyond its side walls to form a flange, said flange being supported on the upper margin of said wall, and the other drums being suspended solely from said upper drum by means of sections of feed-pipes extending between and having screw-threaded connection centrally with the drums, said other drums being provided at their upper ends with radial annular flanges which extend beyond said side walls of the drums but not in contact with the wall of the shell.

2. A water-heater comprising a combustion-chamber, an outer shell extending upwardly therefrom, and a series of water-drums within said shell, the uppermost of said drums having its upper end wall extended beyond its side wall to form a flange, said flange being secured on the upper margin of said shell, and the other drums being suspended in series

from said upper drum and having no contact with said shell, each drum having its upper end wall extended beyond the side wall to form an annular flange having an external 5 diameter less than the internal diameter of the shell.

3. A water-heater comprising a combustion-chamber, an outer shell extending upwardly therefrom, a series of water-drums within 10 said shell, the uppermost of said drums being supported on said shell, and the other drums being supported solely therefrom by means of short sections of feed-pipes which extend between and have screw-threaded 15 engagement centrally with the drums, said drums being provided with a plurality of vertical, conical flues, and the flues of each drum being staggered with respect to the flues of the adjacent drum or drums.

20 4. A water-heater comprising a combustion-chamber, an outer shell extending upwardly therefrom, and a series of water-drums within said shell, said drums each comprising a cylindrical side wall, an upper end wall extending 25 beyond said side wall to form a horizontal annular flange, said flange on the upper drum extending over the upper margin of the outer shell, and being supported thereon, and said flange on each of the other drums 30 having an external diameter less than the internal diameter of the shell, a plurality of

vertical, conical flues symmetrically disposed extending through the drum, and an interior, horizontal deflector-plate centrally supported in the drum by the flues, the drums being 35 connected each to each by the sections of a central feed-pipe, and the flues of each drum being staggered with relation to the flues of the adjacent drum or drums.

5. A water-heater comprising a combustion-chamber, an outer shell extending upwardly therefrom, a series of drums in said shell, the uppermost of said drums being supported by 40 said shell, and the drums each comprising a cylindrical side wall, horizontal end walls, a 45 horizontal annular flange extending beyond the side wall to near the inner surface of the shell, conical flues extending through the drums from end to end and a central, apertured, outwardly-projecting boss on each end 50 wall, and feed-pipes, each having screw-threaded engagement at either end with the bosses of adjacent drums.

In testimony that I claim the foregoing as my invention I affix my signature, in presence 55 of two witnesses, this 21st day of March, A. D. 1901.

RICHARD BEAUMONT.
